OIL BURNER STARTING AND CONTROL
MECHANISM

Anthony A. Avampato, Torrington, Conn.

Application April 16, 1941, Serial No. 388,915

10 Claims. (Cl. 158—28)

This invention relates to oil burners and more particularly to an improved starting and control mechanism therefor.

One object is to provide an oil burner starting and control mechanism of the above nature having means to preheat the oil in the burner for a predetermined length of time and having automatically operated means to subsequently ignite the vapors from the preheated oil.

Another object is to provide an oil burner control apparatus of the above nature having manually-set means to control the relative periods of operation of the preheating means and vapor ignition means.

A further object of this invention is to provide an apparatus of the above nature which will be relatively inexpensive to manufacture, simple in construction, compact, and very efficient and durable in use.

With these and other objects in view which will appear as the description proceeds, there has been illustrated in the accompanying drawings one form in which the invention may be conveniently embodied in practice.

In the drawings:

Fig. 1 is a side view partly diagrammatic, of an oil burner and control apparatus therefor embodying the features and principles of this invention.

Fig. 2 is a top view of the oil flow control valve.

Fig. 3 is a top view of the time-controlled preheating and ignition control means.

Fig. 4 is a diagram of the electrical circuit layout and the control timing means.

Fig. 5 is a side view of one of the control units.

Referring now to the drawings wherein like reference numerals designate like parts throughout the several views the numeral 10 indicates a range type oil burner including in its structure four concentric perforated shells 11, 12, 13, and 14 which are seated on a base plate 15. The base plate 15 is provided with a pair of interconnected concentric oil receiving channels 16 and 17 which are fed by a supply pipe 18 connected to a flexible pipe 19 leading to a manually actuated oil control valve 20, which in turn is connected to an adjustable and automatically controlled oil valve 21 by a pipe 22. The valve 21 is in turn connected to an elevated oil supply container 23 by a pipe 24.

The base plate 15 is seated upon a sub-base plate 25 having cored-out openings 26 enclosing a coil of resistance heating wire 27, the latter serving to heat the sub-base plate 25 and the base plate 15 to bring the oil in the channels 16

and 17 up to a vaporizing temperature. A spark plug 28 passes through the burner shell 14 and has an air gap 29 across which electric sparks may be continuously passed to ignite the oil vapors arising from the heated oil below it.

The automatically controlled oil valve 21 is adapted to be manually "set" by a knob 30 of a dial 31, and is subject to the thermostat control of a fluid pressure bulb 32 disposed over the top of the burner 10. The bulb 32 is connected by a flexible tube 33 to suitable means within the valve 21 for controlling the flow of oil in inverse proportion to the heat developed by the burner 10, i. e., an increase in pressure due to excessive heat from the burner will cause a reduction of the oil fed into the pipe 22 and thence to the burner 10, and vice versa.

An electric cable of two conductors 34 and 35 connects the heating coil 27 with a line connecting plug 36 and a switch control contact 37 respectively. A similar cable of two conductors 38 and 39 connects the spark plug gap 29 with the ends of a secondary coil 40 of a transformer 41. The primary coil 42 of the transformer 41 is connected by suitable conductors 43 and 44 with the line connecting plug 36 and a control contact 45 which is shorter than said contact 37 (see Fig. 4).

The switch contacts 37 and 45 are arcuate in shape and are rigidly mounted on stationary supports 46 and 47 respectively, which are disposed in a preheating and ignition control box 48 supported on a pedestal 49 disposed adjacent the stove frame 50, in which the burner 10 is located.

A dial 51 is provided on the outer surface of one end of the ignition control box 48 and has an indicating pointer 52 associated therewith. The pointer 52 is secured on the outer end of a common shaft 53 which extends through the box 48, and is adapted to be driven by a spring 54 of a timer mechanism of the usual release action type whereby the spring 54 is wound up when the pointer 52 is rotated, and during the reverse rotation the pointer is adapted to indicate the lapse of predetermined time periods. Thus, if the pointer 52 is manually rotated to the point on the dial reading "15" it will take fifteen minutes of reverse rotation of the pointer 52 for it to again reach zero on the dial 51 (see dotted lines in Fig. 4).

A movable switch contact finger 55 is secured on the shaft 53 within the box 48 in position to ride over the arcuate contact 37, and a similar contact finger 56 is secured on said shaft 53 in

position to ride over the arcuate contact 45. Both of the contacts 37 and 45 are connected by a conductor 57 to the plug 36.

As herein illustrated, the arcuate contact 37, connected to the heating coil 27, is of sufficient length to be engaged by the movable finger 55 for a time period of fifteen minutes, while the length of the contact 45 is of sufficient length to be engaged by the finger 56 for a time period of five minutes. Moreover, the contacts are so disposed in relation to each other as herein illustrated that the contact 37 will be engaged by the finger 55 five minutes before the finger 56 contacts the contact 45 and will remain in contact with the finger 55 for five minutes after the finger 56 has moved out of contact with the contact 45. By means of this arrangement, the oil in the burner will be preheated for a predetermined period before the ignition spark is turned on—the lengths of the respective preheating and sparking periods being readily adjustable as desired.

In order to prevent the contact finger 56 from engaging the contact 45 during the setting of the pointer 52 in respect to the dial, if desired, means is provided to lift the finger 56, during its forward travel, while being moved into "set" position. This means comprises an arcuate inclined insulating bar 58 concentric with the contact 45. The end 59 of the bar 58 is adapted to be engaged by the end 60 of the finger 56 to raise said finger out of engagement with the contact 45. The other end 61 of the bar 58 extends beyond the contact 45 and permits the finger 56 to drop onto the insulating support 47 beyond said contact 45. When the reverse rotation of the finger 56 takes place the end 60 of the finger 56 rides under the bar end 61 and engages the contact 45 to close the circuit through the primary coil of the transformer 41 and causes sparks to pass across the air gap 29 of the spark plug continuously.

Operation

In operation, the burner 10 may be started by first opening the manually controlled valve 20 by the proper manipulation of its hand wheel 62. Oil will thereby be permitted to flow by gravity from the supply container 23 through the pipe 24, the control valve 21, the pipe 22, valve 29, pipe 19, and connection 18 into the oil burner channels 16 and 17. The pointer 52 of the preheater and ignition contact unit 48 will then be rotated clockwise, to the point "15" on the dial 51 (as indicated by dotted lines in Fig. 4), the engagement of the contact finger 55 with the arcuate contact 37 closing the circuit through the oil preheating coil 27. After a preheating period of five minutes, the contact finger 56 will engage the stationary arcuate contact 45 to energize the transformer 41 and cause continuous sparking at the gap 29 to ignite the vapor from the preheated oil and start the oil burner. The heating current passing through the resistance coil 27 will be automatically shut off as soon as the timer pointer reaches the zero point, at which time the finger 55 will leave the arcuate contact 37. The burner will then continue to operate under the control of the thermostatically-actuated valve 21.

One advantage of the present invention is that the timer pointer 52 may be set at any desired point on the dial 51 depending upon the predetermined requirements. Moreover, the length of the arcuate contacts 37 and 45 may be varied

to provide for shorter or longer preheating and sparking periods. The relative positions of the contacts 37 and 45 may also be varied with the spirit and scope of the invention.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to obtain Letters Patent is:

1. In a range-type oil burner, an oil-vapor enclosing shell, an oil channel therebeneath, means to preheat oil in said oil channel to vaporize it, a spark plug extending into said shell, and timed manually-set means to energize said preheating means and said spark plug to ignite oil vapor formed by the action of said preheating means, in a predetermined sequence.

2. In a range-type oil burner, an oil containing base, an oil vapor enclosing shell resting on said base, means to preheat oil in said base, a spark plug in said shell, means to control the period of preheating, and timed manually-set means to energize said spark plug after a predetermined period of operation of said preheating means.

3. In a range-type oil burner, a base containing an oil chamber, a shell supported by said base, means to preheat oil in said spark plug in said shell, means to energize said spark plug, and timed manually-set means to control the times of starting, and periods of operation of said preheating means, and said spark plug.

4. In a range-type oil burner, a base provided with an oil channel, a shell located above said base, means to preheat oil in said channel to vaporize it, a spark plug in said shell, means to cause continuous sparking of said spark plug, and manually adjustable settable means to control the times of starting and termination of said preheating means, and said spark plug.

5. In a range-type oil burner, a base having an oil channel, a shell above said base, means to preheat oil in said channel to vaporize it, a spark plug in said shell, said oil preheating means comprising an electrical resistance coil unit, a transformer for continuously energizing said spark plug, and manually-set adjustable means to control the relative periods of operation of said preheating means and said spark plug.

6. In a range-type oil burner, a base having an oil channel, a shell located above said base, electrical means to preheat oil in said channel to vaporize it, a spark plug in said shell, a transformer for energizing said spark plug, manually-set adjustable means to control the relative periods of operation of said preheating means and said spark plug.

7. In a range-type oil burner, an oil containing base, an oil vapor enclosing shell resting on said base, means to preheat oil in said base, a spark plug in said shell, means to control the period of preheating, and manually-set adjustable timed means to continuously energize said spark plug after a predetermined period of operation of said preheating means.

8. In a range-type oil burner, a base having an oil channel, a shell located above said base, electrical means to preheat the oil in said chan-

nel, a spark plug in said shell to ignite the vaporized oil therein, and manually-set adjustable timer means to control the relative periods of operation of said preheating means and said spark plug comprising an electric circuit including said preheating means, an electric circuit including a transformer for energizing said spark plug, said timer means having a common control shaft to which a pair of movable contacts are connected, said movable contacts engaging a pair of arcuate contacts of different lengths located in said preheating and spark plug circuits, respectively.

9. In an oil burner, a base having an oil channel, a shell located above said base, electrical means to preheat the oil in said channel, a spark plug in said shell to ignite the vaporized oil therein, a timer means to control the relative periods of operation of said preheating means and said spark plug comprising an electric cir- 20

cuit including said preheating means, an electric circuit including a transformer for energizing said spark plug, said timer means having a common control shaft to which a pair of movable contacts are connected, said movable contacts engaging a pair of arcuate contacts of different lengths located in said preheating and spark circuits, respectively, and means to prevent said spark plug circuit contacts from engaging each other when said timer shaft is moved to "set" position.

10. In a range-type oil burner, an oil containing base, an oil vapor enclosing shell resting on said base, means to preheat oil in said base, a spark plug in said shell, manually-set means to control the period of preheating, and manually-set timed means to continuously energize said spark plug after a predetermined period of operation of said preheating means.
